UNITED STATES PATENT OFFICE.

LEWIS ALVERSON, OF DALLAS, TEXAS, ASSIGNOR TO MARTIN O. SHOOP, OF ST. PAUL, MINNESOTA.

FENCE-STAY MACHINE.

1,290,477.

Specification of Letters Patent.

Patented Jan. 7, 1919.

Application filed February 5, 1917. Serial No. 146,687.

To all whom it may concern:

Be it known that I, LEWIS ALVERSON, a citizen of the United States, residing at Dallas, in the county of Dallas and State of Texas, have invented certain new and useful Improvements in Fence-Stay Machines, of which the following is a specification.

My invention has relation to a machine for making wire fence stays.

10 This invention relates more particularly to a machine for making fence stays wherein a revolving tubular member is arranged to receive internally one portion of a straight or substantially straight wire and wherein 15 the machine is provided with means for coiling the remaining portion of the wire around the tubular member and hence around the straight portion of the wire within the tubular member.

20 While I have, in the present application, embodied in my improved machine, these elements in substance, the main objects of my present invention may be summarized as follows:

25 First, to so reorganize and rearrange certain of the parts of the machine that the same may be more compact and better adapted for transportation from place to place as required.

30 Second, to so change and rearrange the driving mechanism of the machine that the machine may be operated from the front instead of from the end, as heretofore, whereby a saving in length of the machine as well 35 as a simplification of parts of the driving mechanism may be secured; and

35 Third, to provide in the machine a new arrangement and construction of parts constituting the means whereby the carriage at 40 the end of its positive movement in one direction will disconnect the carriage driving mechanism from the gear revolving the tubular member to permit of the tension or spring means operating to return the carriage to its normal or initial position.

45 The nature and scope of my invention will be more fully understood from the following description taken in connection with the accompanying drawings, forming part hereof, in which—

Figure 1 is a top or plan view of a machine embodying the main features of my invention;

Fig. 2 is a front elevational view, partly sectioned, of the same;

Fig. 3 is an end elevational view, partly in section, illustrating in detail the clutch mechanism for connecting the driving gear with the chain for positively moving the carriage in one direction; and

Fig. 4 is a detail view of the tubular member and stay disconnected from the machine.

Referring to the drawings 1 represents the base of the machine formed of any suitable material and hollowed out as at 2 to receive the spring or tensioning means for returning the carriage 3 to its initial or normal position. The carriage 3 slides back and forth upon a bar or frame 4 supported at either end by the brackets or standards 5 and 6 respectively, which project upward from and are fixed to the upper face of the base 1 of the machine. The rear standard 6 forms a bearing for a stub shaft 7 having a sprocket wheel 8, and the bracket 5 forms a bearing 65 for a shaft 9 on which is secured a miter gear wheel 10 operated preferably by a crank or handle 11 or by any suitable power-driven means if desired.

The miter gear wheel 10 is always in mesh 70 with a similar but smaller gear wheel 12, secured to one end of a tubular member 18, the member 13 revolving when the miter gear 12 turns in a bearing formed in the bracket 5 and in the carriage 3 which the tubular member 13 traverses.

The shaft 9 carries a collar 14 outside the bearing in standard 5, and this collar is arranged to be locked to a clutch sleeve 15, which sleeve is arranged to turn loosely on the shaft 9 when not so locked and to slide longitudinally on said shaft to engage with or disengage from the collar 14. A preferred form of locking means between the sleeve 15 and collar 14 is constituted by a pin 90 95 16 on sleeve 15 entering a recess of the collar 14.

The sleeve 15 is provided with an extension 17 which carries a sprocket wheel 18 and a chain 19 connects the two sprocket wheels 100 8 and 18 together. The carriage 3 is provided with a clip 3^a which secures the carriage 3 to said chain 19. It follows that when the sleeve 15 with its sprocket 18 is locked to shaft 9 and said shaft is turned, 105 the chain 19 in revolving will draw the car-

- riage 3 along the guide bar or frame 4 and along the tubular member 13 toward the bracket or standard 5.
- To hold the sleeve 15 with its extension 17 and sprocket wheel 18 in locking engagement with collar 14 during the driving of the chain 19 and the movement of the carriage toward bracket 5, there is provided a tubular cap 20 splined to the shaft 9 and adapted to be pushed inward on the shaft to bear against the extension 17 of sleeve 15 and to slide outward on said shaft when the clutch sleeve 15 is withdrawn from locking engagement with the collar 14.
- 15 The means for disconnecting the clutch sleeve 15 from collar 14 consists, as very clearly shown in Fig. 1, of a wedge-shaped pin or bolt 21 sliding in a bracket 22 arranged on the standard 5 adjacent to the collar 14. A coiled spring 23 normally holds said bolt 21 in retracted position in the bracket 22, or away from the junction between collar 14 and sleeve 15. The bolt 21 has a rod 24 projecting through bracket 22 and beyond the same into the path of the approaching carriage 3. The carriage at the limit of its movement toward standard 5 impinges on the rod 24 and thus forces bolt 21 into the joint between collar 14 and sleeve 15 to thereby disengage the sleeve from the collar and hence from the shaft 9. The spring 23 will retract bolt 21 after the carriage 3 has been drawn backward to its initial or starting point. The sleeve 15 may thereafter be brought into locking engagement with the collar 14 by pushing the tubular cap 20 inward on the shaft 9.
- The means for retracting the carriage 3 comprises the cord 30 attached at one end to the carriage 3 and passing over successive pulleys 31, 32 and 33 and then attached at its other end to the base of the machine. Pulley 33 is attached to one end of a coiled spring 34, the other end of the spring 34 being attached to the base 1 of the machine. When the carriage advances on its guide way, the cord 30 extends the spiral spring 34, but when the clutch sleeve 15 and its sprocket are released from shaft 9, the cord 30 under influence of the spring 34 will retract the carriage 3. On the guide bar 4 is arranged a buffer 35 which acts as a stop to limit the return movement of the carriage 3. The buffer 35 has a ring-shaped extension 36 with a slot 37. The end of the member 13 revolves within the extension 36 and the wire 40 of the stay is drawn back from the end of tubular member 13 through the slot 37 and threaded through a recess 41 in carriage 3 at the initial movement of the machine. To prevent rotation of the straight portion of the stay inside the tubular member the wire 40 is bent back-ward in a V-shaped notch 42 formed in the end of member 13 before the wire is passed 65 through the carriage 3.
- Having thus described the nature and objects of my invention, what I claim as new and desire to secure by Letters Patent, is—
1. In a fence stay machine, a tubular member arranged to receive a portion of a straight wire, a carriage adapted to be advanced along the exterior of said tubular member to coil the remaining portion of the wire around said member, a means for revolving said tubular member comprising a shaft, a miter gear fixed to said shaft, and a miter gear on the tubular member meshing with said miter gear of the shaft, and a means for advancing the carriage comprising a sprocket wheel detachably locked to said shaft, a second sprocket arranged at the end of the machine opposite to the shaft, a chain traveling over said sprockets, and a clip connecting the carriage with said chain. 70 75 80 85
2. In a fence stay machine, a tubular member arranged to receive a portion of a straight wire, a carriage adapted to be advanced along the exterior of said tubular member to coil the remaining portion of the wire around said member, a means for revolving said tubular member comprising a shaft, a miter gear fixed to said shaft, and a miter gear on the tubular member meshing with said miter gear of the shaft, and a means for advancing the carriage comprising a sprocket wheel detachably locked to said shaft, a second sprocket arranged at the end of the machine opposite to the shaft, a chain traveling over said sprockets, and a clip connecting the carriage with said chain. 90 95 100 105
3. In a fence stay machine, a driven shaft, a tubular member, intermediate gearing connecting the member with said shaft and arranged to revolve said member as said driven shaft revolves, a collar revolving with said shaft, a sleeve loosely surrounding said shaft and arranged to be detachably locked to said collar, a wedge-shaped bolt arranged to separate the sleeve from said collar, a sprocket wheel carried by said sleeve, a chain operated by the sprocket wheel when said sprocket wheel revolves with the sleeve, and a carriage carried by the chain and adapted to be advanced on the tubular member when said sprocket chain revolves, in 110 115 120 combination with a spring-controlled pin carried by the bolt and extending into the path of the carriage. 120
- In testimony whereof I have signed my name to this specification.
- LEWIS ALVERSON.
